SPRAY NOZZLE

Donald J. Peeps, Toledo, Ohio, assignor to The
De Vilbiss Company, Toledo, Ohio, a corpora-
tion of Ohio

Application May 29, 1944, Serial No. 537,918

1 Claim. (Cl. 299—143)

1

This invention relates to nozzles for spray coating devices using air for atomizing the coating material and particularly to such nozzles having an atomizing and discharging chamber with a plurality of outlet ports for discharging the atomized material in a plurality of directions.

A nozzle of this general type is the subject of my co-pending application No. 421,140 filed December 1, 1941, Patent Number 2,356,944.

Difficulty has been encountered with the nozzles described in this previous application in regard to supplying sufficient material to the rearwardly directed discharge ports.

The primary purpose of this invention is to overcome this difficulty.

Another object of the invention is to arrange the discharge ports so as to increase the coating scope in regard to cavities having variously facing surfaces within a limited space.

The design of a nozzle, utilizing air for atomizing and discharging a coating material, is quite technical in view of the two fluids involved and the fact that the proportion of liquid to air is very low-frequently as small as one per cent and averaging little more than that. The feeding pressures, the velocities, weight and proportions of the two fluids all affect results obtained. Naturally the specifications of such a nozzle may not be determined from results obtained with a hydraulic type of nozzle handling a liquid alone. Such a fluid not having the compressibility of air or of a mixture of air and liquid, is more inclined to react uniformly throughout a circuit to a change in pressure, direction or velocity. While a liquid alone issuing from a port under pressure spreads only slightly, when particles of coating liquid are dispersed through compressed air they will be spread considerably with the expanding air as the mixture is discharged.

Other objects of the invention will appear from the following specification and the accompanying drawings in which:

Figure 1 is a longitudinal sectional view of a spray gun extension with a discharge nozzle embodying my invention;

Figure 2 is a front elevation of the nozzle on the extension of Figure 1;

Figure 3 is a side elevational view of the discharge nozzle of Figures 1 and 2;

Figure 4 is a front elevation of another form of nozzle embodying my invention;

Figure 5 is a side elevational view of the nozzle shown in Figure 4;

Figure 6 is a front elevation of a third form of nozzle embodying my invention;

2

Figure 7 is a side elevational view of the nozzle in Figure 6;

Figure 8 is a somewhat schematic presentation of a spray gun extension with a nozzle of my invention applying coatings to various interior surfaces of a shell.

The spray gun extension shown in Figure 1 has an exterior air tube 1 to which is fastened an air tip 2. Within the tube 1 and the tip 2 are liquid tubes 3 and 4, to the latter of which is fastened a liquid tip 5.

The end of the liquid close-off needle valve 6 is shown seated within the inner end of the tube 4. Upon the air tip 2 is attached a liquid and air, mixing and discharge nozzle 7. Liquid enters this nozzle from the liquid tip 5 and air enters the nozzle from the annular air passage formed between the liquid tip 5 and the air tip 2. Within the nozzle 7, immediately ahead of the tips 2 and 5, is a 10 cylindrical chamber 8. At the forward end this chamber has a tapered or converging section 9. In this converging wall section is an annular series of six equally spaced ports 10 directed forwardly at an angle of approximately 60° to the 15 longitudinal axis of the nozzle. Beyond these ports is a second cylindrical chamber 11 with a diameter smaller than that of chamber 8. At the forward end of this chamber the wall has a converging section 12. From this section there is 20 another annular series of six ports 13 directed rearwardly at an angle of approximately 60° to the axis of the nozzle. These ports 13 are in staggered relation to the ports 10 whereby the atomized material discharged from them will pass 25 between jets of atomized material coming from ports 10. Beyond the converging wall section 12 is a short cylindrical section 14 with a diameter less than the diameter of the chamber 11. From the section 14 the walls of the nozzle expand to a 30 diameter greater than that of chamber 8 and then 35 contract to merge and form a rounded end.

From the chamber 15 thus formed six ports 16 are directed forwardly. The arrangement of the ports 16 may be seen more clearly in Figures 2 and 45 3 which present other views of the atomizing and discharge nozzle shown in Figure 1.

In Figures 2 and 3 the nozzle is turned on its longitudinal axis about 90° from the position in which it is shown in Figure 1.

50 The nozzle shown in Figures 4 and 5 has, instead of the forwardly directed round discharge ports 16, a slot 17. While having the lateral ports 13 directed rearwardly it does not have the forwardly directed lateral ports 10. In Figures 6 and 55 7 is a third form of my invention in which the nozzle

zle has three slots discharging from the large end chamber. One of these slots indicated at 18 is centrally positioned like slot 17 in the nozzle in Figures 4 and 5, while the other two 19 are placed on opposite sides of the first slot. Instead of having rearwardly directed ports 13 the nozzle shown in these figures has a slot 20 discharging from the center portion of the nozzle and directed rearwardly. The interior shape of the nozzles of Figures 4, 5, 6, and 7 is the same as that of the nozzle of Figure 1 except for the omission of the short initial cylindrical passage 8 and the converging section 9.

The nozzle shown on the extension in Figure 8 is the same as that of Figures 1, 2 and 3. When such a nozzle is used for coating interior surfaces of a cavity, such as the interior of a shell 21 as indicated, either the shell or the nozzle is revolved while relative movement along their common longitudinal axis brings the nozzle within the shell. As indicated material discharged from the ports 16 coat the interior end 22 of the cavity while spray material issuing from the forwardly inclined ports 10 coat surfaces 23 which face rearwardly of the nozzle and material discharged by rearwardly directed ports 13 coat surfaces 24 facing forwardly of the nozzle.

As the shell 21 or the nozzle rotates in relation to the other and relative movement occurs between the shell and the nozzle along their common longitudinal axis, spray patterns directed laterally from ports 10 and 13 sweep around the interior surfaces of the shell overlapping on each turn and progressively coat the surfaces toward which they are directed. Simultaneously the further interior end of the shell is coated by material issuing from the forward ports 16 of the nozzle.

In previously designed nozzles having ports positioned to discharge in varying directions, those ports directed more in line with the forward movement of the atomizing material through the nozzle have received proportionately more of the material than other ports and because of this the coating thus obtained has not been evenly applied. In order to secure a more desirable division of the material discharged by the various ports applicant has evolved the nozzle shown herein in which a restriction is positioned in the nozzle after each set of ports. This tends to hold back the forward flow of atomized material sufficiently to provide the ports with the proper amount of material. The balance of the atomizing material proceeds to each successive series or set of ports which in turn is provided with its restriction designed to hold back sufficient material. The final residue of material reaches the end ports and is discharged therefrom.

By having the forwardly inclined lateral ports positioned rearwardly of the rearwardly inclined lateral ports, material discharged by these two

sets of ports travel along converging paths and is deposited within a more confined area. This arrangement reduces the longitudinal movement necessary between the nozzle and shell and also enables the nozzle to be used on a shell cavity, the opposed surfaces of which are too close to coat otherwise. It is of course necessary, should the paths of the jets cross, that the jets of atomized material do not meet nor interfere with each other. The ports of one series are therefore staggered in relation to those of the other series and the jets of material from one series pass between the jets from the other set while traveling toward the surface.

While several specific embodiments of the invention are shown and described herein, it will be understood that various changes in the size, shape, position and number of orifices of such nozzles, as well as in the shape of the interior of the nozzle without departing from the spirit of the invention.

Having thus described my invention what I claim as new and desire to secure by Letters Patent is:

25 In a spray nozzle utilizing air for atomizing and directing coating material upon surfaces facing in various directions, the rear end of the nozzle being adapted to communicate with a source of supply for the air and material, a mixing and discharge chamber extending axially through the nozzle from said end, an intermediate elongated cylindrical section of the chamber, an enlarged forward end of the chamber with a diameter greater than that of the cylindrical section, an 35 inwardly extending truncated annular ridge forming a restricted communicating passage between the cylindrical section and the enlarged forward end of the chamber, forwardly directed discharge port means in the enlarged forward end of the chamber, and laterally directed discharge port means in the chamber immediately to the rear of the restricting ridge.
